UNITED STATES PATENT OFFICE.

FREDERICK D. BUFFUM, OF COLUMBUS, OHIO, ASSIGNOR, BY MESNE ASSIGNMENTS, TO THE JEFFREY MANUFACTURING COMPANY, A CORPORATION OF OHIO.

BOX-CAR-LOADING APPARATUS.

No. 914,017.

Specification of Letters Patent.

Patented March 2, 1909.

Application filed February 10, 1903, Serial No. 142,770. Renewed July 23, 1908. Serial No. 445,044.

To all whom it may concern:

Be it known that I, FREDERICK D. BUFFUM, of Columbus, in the county of Franklin and State of Ohio, have invented certain new and 5 useful Improvements in Box-Car-Loading Apparatus, of which the following is a specification.

This invention relates to devices for depositing material in railroad freight-cars of 10 the box-car type, and has for its object to enable material such as coal to be deposited simultaneously at two different parts of the car, said parts being between the center and the ends of the car, so that the capacity of the 15 loading apparatus is increased and the time required to load the car reduced to the minimum.

Means for loading coal into box-cars are 20 desirable, because "flat cars" so-called are not always available, and further because box-cars render the coal more secure from theft in transit and protect it from the weather.

My invention as above indicated is embodied in an apparatus adapted to load both 25 ends of the car at the same time, and it consists in the improvements which I will now proceed to describe and claim.

Of the drawings accompanying this specification and forming a part thereof,—Figure 1 represents a side elevation of a loading apparatus embodying my improvements, in position to receive coal from a chute and deposit the coal in the ends of the car, the latter 35 being shown in cross-section. Fig. 2 represents a plan view of the loading apparatus, arranged to enter the car through one of the side doors. Fig. 3 represents a partial section on line 2—2 of Fig. 2, parts being shown in 40 elevation. Fig. 4 represents an enlarged section of a portion of the apparatus, on line 4—4 of Fig. 5. Fig. 5 represents a plan view of the portion of the apparatus shown in Fig. 4. Fig. 6 represents a section on line 6—6 of 45 Fig. 1, showing the supports of the loader in section. Fig. 7 represents a section on line 7—7 of Fig. 6. Fig. 8 represents a section on line 8—8 of Fig. 1, looking downwardly.

The same reference characters indicate the 50 same parts in all the figures.

In the drawings,—*a* represents a fixed supporting frame, to which are affixed parallel track-rails *b* extending at right angles with the rails *b'* of the railway-track supporting the car *j* to be loaded.

c represents a carriage, having wheels *d* affixed to axles 3 and adapted to run on the track - rails *b*, said carriage having means hereinafter described, whereby it may be moved endwise upon the rails *b* in either 60 direction, to project the forward end of the carriage into and withdraw it from the car. Upon the forward end of the carriage is located the part of the apparatus hereinafter termed the loader, the same being indicated 65 as a whole by the letter *e*. Said loader in this embodiment of my invention comprises a hopper *f* supported upon a turn-table *f'* resting upon a seat *f''* secured to the carriage. The hopper is provided with openings *f''* *f''* 70 at each end, for the delivery of coal to the car. The hopper supports two endless conveyors *f''* *f''* adapted to convey two streams of coal from the center of the hopper outwardly to the delivering ends thereof, the coal being 75 delivered to the hopper by a chute *f'* inserted in one of the side doors of the car. The turn - table *f'* is adapted to be partially rotated on the seat *f''* to cause the hopper to extend lengthwise of the car after it has been 80 projected into the car, the hopper being adjusted so that it extends lengthwise of the carriage while entering the car, and crosswise of the carriage when adjusted to load the car. The conveyors are moved simultaneously 85 in the directions indicated by the arrows in Fig. 4, to distribute the material, by the means next described.

Journaled in a vertical bearing formed in the seat *f''* and occupying the center of rotation of the turn-table, is a vertical shaft *g*, provided at its lower end with a sprocket-wheel *g'*, with which is engaged a chain *g''* driven by sprocket-wheel *g''* on a vertical shaft *g''* mounted in bearings upon the carriage. The shaft *g''* is provided with a bevel-gear *g''* meshing with a bevel-gear *g''* on a horizontal shaft *g''* also journaled in bearings on the carriage and driven by a suitable electric or other motor *g''* supported by the 90 carriage. The upper end of the vertical shaft *g* is 95 mounted a bevel-gear *g''* meshing with bevel-gears *h* *h'* (Fig. 7) affixed respectively to short horizontal inner shafts *h''* *h''* journaled in suitable bearings on the turn-table *f'* and having upon their outer ends sprocket-wheels *h''* *h''* engaged with sprocket-chains *h''* *h''*, said chains engaging sprocket-wheels *h''* *h''* mounted upon outer horizontal shafts *h''* 100

105

On the upper end of the vertical shaft *g* is mounted a bevel-gear *g''* meshing with bevel-gears *h* *h'* (Fig. 7) affixed respectively to short horizontal inner shafts *h''* *h''* journaled in suitable bearings on the turn-table *f'* and having upon their outer ends sprocket-wheels *h''* *h''* engaged with sprocket-chains *h''* *h''*, said chains engaging sprocket-wheels *h''* *h''* mounted upon outer horizontal shafts *h''* 110

h^8 journaled in bearings at the end portions of the hopper. Said shafts h^8 h^8 have sprocket-wheels i^8 i^8 , which are engaged by sprocket-chains i^2 engaging sprocket-wheels i^3 upon inner supporting shafts i^4 journaled in bearings on the turn-table. There are two pairs of chains i^2 , the chains of each pair carrying cross-pieces or slats i^5 , one pair of chains and its cross-pieces constituting the conveyer f^5 , while the other pair of chains and its cross-pieces constitute the conveyer f^6 . Each conveyer is preferably provided with outwardly projecting flanges or ribs f^8 to engage the material and prevent it from gravitating on the inclined acting stretches of the conveyers.

In Fig. 4, I have shown the hopper as provided with an angular shield or deflector i^8 to receive the impact of the coal from the delivery-chute and cause the same to flow in opposite directions to the conveyers, so that a substantially equal amount is deposited upon each conveyer. Said shield prevents the coal from coming in contact with the gearing below it.

In Figs. 3 and 6, I show means for adjusting the outer supporting shafts h^8 laterally to increase their distance from the inner supporting shafts, and thus compensate for or take up wear in the sprocket-chains h^8 for the purpose of preventing the excessive noise due to the rattle which would attend the rapid movement of the chains if any considerable looseness existed at their joints, the chains being driven at high speeds, sometimes as high as sixteen hundred feet per minute. The ends of the shafts h^8 project into slots h^{10} in the sides of the hopper. In said slots are sliding bearings h^{12} interposed between the shafts h^8 and the inner ends of the slots. Said boxes are adjustably supported by screws h^{13} engaged with tapped sockets on the sides of the hopper. Rotation of the screws in the direction required to move the bearings and shafts outwardly will take up the wear of the chains. This is a feature of considerable importance, as the noise attending the rapid movement of a conveyer the chains of which are loose, is almost unbearable. It is obvious that this provision for taking up wear may be employed in connection with a loader having but one conveyer.

The turn-table f' has an annular flange j , which rests upon the seat f^2 and is prevented from displacement, while permitted to rotate, by a ring j' secured to the seat by bolts j^2 , so that when the loader is introduced into the car at right angles to the latter, it may be turned so as to stand lengthwise of the car, as shown in Fig. 8.

The carriage c is provided with means for communicating motion from the motor g^8 to one of the axles 3 of the carriage, for the purpose of moving the carriage along the rails b

in either direction to project the loader into and withdraw it from the car. The means here shown comprise a gear 2 (Fig. 2) mounted on one of the axles 3 (termed the driving axle) and meshing with a pinion 4 on a shaft 5 journaled in bearings on the carriage. To one end of the shaft 5 is affixed a bevel-gear 6 meshing with two gears 7 8 loosely mounted upon the driving-shaft g^7 and adapted to rotate said shaft in either direction when brought into engagement with a clutch 9 splined upon the shaft and operated by a lever 10 engaged with the clutch, a hand-lever 11 , and a rod 15 connecting said levers (Fig. 2). When the clutch 9 is engaged with the bevel-gear 7 , motion is communicated through said gear and the intermediate connections, to the driving-axle 3 , and the carriage c is moved in one direction, the gear 8 rotating loosely. When the clutch 9 is engaged with the bevel-gear 8 , motion is communicated in the opposite direction to the driving axle, and the carriage is moved in the opposite direction, the gear 7 rotating loosely. Means are also provided for communicating motion from the motor g^8 to the chute f^7 to project the same into and withdraw it from the car, the chute being provided with wheels f^8 mounted on track-rails f^9 extending at right angles with the rails b' of the car-track. Said means are as follows: A drum k is mounted upon a shaft k' journaled in bearings on the carriage and having a bevel-gear 60 meshing with loose bevel-gears 70 80 on the driving-shaft. A clutch member 90 between said bevel-gears is splined to the driving-shaft and adapted to slide thereon and engage complementary clutch members on the gears 70 80 , said sliding clutch member being movable by a lever 100 engaged therewith and a hand-lever 111 connected by a rod 16 with the lever 100 . A rope or chain k^2 (Fig. 1) is attached at its ends to the drum k , and passes over a series of pulleys k^3 , the arrangement of the pulleys and rope being such that when the drum k is rotated in one direction, the chute is projected into the car, and when the drum is rotated in the opposite direction the chute is withdrawn from the car. The rope k^2 constitutes a flexible connection between the carriage and the chute. I have provided an indicator, to enable the operator standing at the levers 11 111 , which are at the opposite side of the car from the chute, to determine the extent of projection of the chute into the car. Said indicator comprises a fixed vertical graduated scale l^3 located near the operator's station, and a plummet l movable vertically beside the scale l^3 and suspended from a rope l' attached to the chute and guided by pulleys l^2 . The position of the plummet relatively to the scale enables the operator to know when the chute is sufficiently projected and retracted. Finally, means are provided

- for disconnecting the driving-shaft g^7 from the conveyers when the carriage is being moved to project and withdraw the loader, thus making the conveyers inoperative.
- 5 Said means as here shown comprise a ratchet clutch m having two members m^1 m^2 , the member m^2 being splined upon the shaft and adapted to be moved longitudinally of the same to engage the member m^1 , which is 10 loosely mounted on the driving-shaft but positively connected with the driving-gear g^8 . The members m^1 m^2 are to be disconnected when the loader is being moved into and out of the car by the connection of the driving-shaft with the driving-axle 3, the disconnection of said members rendering the connections between the driving-shaft and the conveyers inoperative. The clutch members m^1 m^2 are to be connected when the loader is in 15 its operative position in the car. The sliding clutch member m^2 is moved by a lever m^3 , a hand-lever m^4 located beside the levers 11 and 111, and a rod m^5 connecting the hand-lever m^4 with the lever m^3 .
- 20 It will be seen that the length of the loader is limited by the width of the car, the total length being necessarily such as to permit the loader to be given a quarter-turn after being inserted in the car. With a car of 25 average length, considerable spaces will exist between the ends of the loader and the ends of the car, as indicated in Fig. 8. By varying the speed of the conveyers, the coal can be deposited at various parts of 30 these spaces, centrifugal force being utilized to throw the coal outwardly from the ends of the conveyers more or less. The coal can therefore be placed as may be desired, the bulk being preferably deposited over the 35 car-trucks.
- 40 I am aware of the fact that heretofore it has been proposed to construct box car loaders with material distributing conveyers arranged to operate in opposite directions so as to deliver the material to both ends of the car simultaneously, but in the earlier forms of mechanisms of which I am aware, the conveyers were either adapted to be 45 adjusted within the car about horizontal axes arranged in vertical planes parallel to the vertical longitudinal planes of the loader carriage or the sections of the material distributing chute-ways were adapted to be folded up relative to each other in order to 50 permit the loader to be inserted into the car and then unfolded for the purpose of distributing to both ends of the car coal delivered to them by a reciprocating mechanism.
- 55 40 I believe I am the first to provide in a box car loading mechanism a longitudinally movable carriage having at its end which is adapted to be inserted into the car a turn-table carrying oppositely arranged material 55 distributing conveyers, the turn table being
- rotatable so as to bring the longitudinal lines of the conveyers into parallelism with the longitudinal lines of the carriage for the purpose of inserting and withdrawing the loader from a car, and the turn table being 70 rotatable after the conveyers are within the car so as to cause them to deliver material to the opposite ends thereof.
- Having thus explained the nature of my invention and described a way of constructing and using the same, although without having attempted to set forth all the forms in which it may be embodied or all the modes of its use, I declare that what I claim is:
- 75 1. A box-car loader comprising a turn-table, a movable support therefor, two endless conveyers supported by the turn-table and extending in opposite directions from its center of rotation, and means for simultaneously moving said conveyers in opposite 80 directions.
2. A box-car loader comprising a turn-table, a movable support therefor, two endless conveyers supported by the turn-table and extending in opposite directions from 90 its center of rotation, means for simultaneously moving said conveyers in opposite directions, and a shield or deflector located over the center of the turn-table and adapted to distribute the material to the two conveyers.
- 95 3. A box-car loader comprising a turn-table, a movable support therefor, a hopper supported by the turn-table and extending in opposite directions from its center of rotation, the hopper having delivery-openings at its ends, two endless conveyers in said hopper extending in opposite directions from points adjacent to the center of the turn-table to said delivery-openings, and means 100 for simultaneously moving said conveyers in opposite directions.
- 105 4. A box-car loader comprising a turn-table, a movable support therefor, a vertical shaft extending through the center of the turn-table, means for rotating said shaft, two endless conveyers supported by the turn-table and extending in opposite directions from said shaft, and connections between said conveyers and shaft, whereby motion 110 is imparted from the shaft to the conveyers simultaneously, the conveyers being moved in opposite directions.
- 115 5. A box-car loader comprising a turn-table, a movable support therefor, a vertical shaft extending through the center of the turn-table, means for rotating said shaft, two endless conveyers supported by the turn-table and extending in opposite directions from said shaft, said conveyers comprising outer horizontal supporting shafts, 120 inner horizontal supporting shafts, and endless chains of strips or slats, inner horizontal driving-shafts geared to the vertical shaft at opposite sides of the latter, and connec- 125
- 130

tions between said outer shafts and the horizontal driving-shafts, whereby the conveyers are moved simultaneously in opposite directions.

6. A box-car loader comprising a turn-table, a movable support therefor, a vertical shaft extending through the center of the turn-table, means for rotating said shaft, two endless conveyers supported by the turn-table and extending in opposite directions from said shaft, said conveyers comprising outer horizontal supporting shafts, inner horizontal supporting shafts, and endless chains of strips or slats, inner horizontal driving-shafts geared to the vertical shaft at opposite sides of the latter, connections between said outer shafts and the horizontal driving-shafts, whereby the conveyers are moved simultaneously in opposite directions, and a shield or deflector located above the vertical and inner horizontal driving-shafts.

7. A box-car loader comprising a carriage, a turn-table at one end of the carriage, load-distributing means carried by the turn-table and adapted to deliver material simultaneously at either side of said carriage, a driving-shaft on the carriage, and movable therewith, a motor on the carriage for rotating said shaft, separable connections between the driving-shaft and the load-distributing means, and separable connections between the driving-shaft and an axle of the carriage, whereby the shaft may be used alternately to operate the load-distributing means and to impel the carriage.

8. A box-car loader comprising a carriage, a turn-table at one end of the carriage, load-distributing means carried by the turn-table, a driving-shaft on the carriage, means for rotating said shaft, a track for the carriage at one side of a railway-track supporting the car to be loaded, a chute movably supported at the opposite side of said railway-track, and means for imparting movement in either direction to the chute from the driving-shaft on the carriage.

9. A box-car loader comprising a carriage, a turn-table at one end of the carriage, load-distributing means carried by the turn-table, a driving-shaft on the carriage, means for rotating said shaft, a track for the carriage at one side of a railway-track supporting the car to be loaded, a chute movably supported at the opposite side of said railway-track, a drum on the carriage, means for imparting movement in either direction from the driving-shaft to the drum, and a flexible connection between the drum and the driving-shaft, whereby movement of the drum in either direction is caused to impart a corresponding movement to the chute.

10. A box-car loader comprising a carriage, a turn-table at one end of the carriage, load-distributing means carried by the turn-

table, a driving-shaft on the carriage, means for rotating said shaft, a track for the carriage at one side of a railway-track supporting the car to be loaded, a chute movably supported at the opposite side of said railway-track, means for imparting movement in either direction to the chute from the driving-shaft on the carriage, and an indicator connected with the chute and operatively related to the carriage.

11. A box-car loader comprising a carriage, a turn-table at one end of the carriage, load-distributing means mounted on said turn-table and adapted to simultaneously deliver material at either side of said carriage, a vertical shaft centrally mounted in said turn-table, a horizontal driving-shaft mounted on the carriage and movable therewith, means for rotating said driving-shaft, a train of power transmitting devices interposed between said driving-shaft and said vertical shaft and having in said train of devices a clutch, and means interposed between said vertical shaft and said load distributing means for actuating the latter.

12. A box-car loader comprising a carriage having a driving axle, a turn-table at one end of the carriage, load-distributing means carried by the turn-table, a driving-shaft on the carriage, and movable therewith, a motor on the carriage for rotating said shaft, separable connections between the driving-shaft and the load-distributing means, reversible connections between the driving-shaft and the driving axle of the car, said connections including clutch members, one of which is movable, and means for adjusting said movable member to impel the carriage either forward or backward, and to make the driving axle inoperative.

13. A box-car loader comprising a carriage, a turn-table at one end of the carriage, load-distributing means carried by the turn-table, a driving-shaft on the carriage, means for rotating said shaft, a track for the carriage at one side of a railway-track supporting the car to be loaded, a chute movably supported at the opposite side of said railway-track, a drum on the carriage, reversible connections between the drum and the driving-shaft, said connections including clutch members, one of which is movable, means for adjusting said movable member to rotate the drum either forward or backward and to make it inoperative, and a flexible connection between the drum and chute.

14. A box-car loading apparatus comprising a track at one side of and at right angles with a railway-track supporting the car to be loaded, a carriage movable on said track, a turn-table on one end of the carriage adapted to be moved by the latter into and out of the car, load-distributing means on the turn-table, a chute movably supported at the opposite side of the car from the turn-table, a mo-

- tor on the carriage, separable connections between the motor and the load-distributing means organized to operate the latter, separable connections between the motor and the chute organized to move the chute into and out of the car, and hand-controlled devices on the car for making each set of connections operative and inoperative.
15. In a box car loader, the combination with a longitudinally moving carriage, of a turn table mounted thereon, a pair of conveyers mounted in fixed relations to each other on the turn table and extending in opposite directions from its center of rotation, and means for simultaneously actuating said conveyers.
16. In a box car loader, the combination with a movable carriage, of a turn table mounted thereon, a pair of conveyers supported on the turn table and extending in opposite directions from its center of rotation, a hopper supported by the turn table and within which the said conveyers are arranged, and means for actuating the conveyers.
- 25 17. In a box car loader, the combination with a movable carriage, of a turn table mounted thereon, a pair of oppositely acting conveyers mounted in fixed relation to each other on the turn table, means for actuating the conveyers and means carried by the turntable for simultaneously directing material to each of said conveyers, substantially as set forth.
18. In a box car loader, the combination with the carriage, the material distributing means thereon adapted to be inserted into and withdrawn from the car through one side thereof and a power driven shaft on said carriage, of a chute adapted to be inserted into and withdrawn from the car through the opposite side thereof from said material distributing means, and to deliver material to the latter, and means for imparting movement in either direction to the said chute from the power driven shaft on the carriage.
19. In a box car loader, the combination with a carriage and material distributing means thereon adapted to be inserted into and withdrawn from a car through one side thereof, of a power driven shaft, a chute arranged to enter the car on the opposite side from that through which said material distributing means enters and adapted to deliver material to the latter, means for imparting movement to the carriage in either direction from said power driven shaft and means for imparting movement in either direction to the chute from said power driven shaft, substantially as set forth.
- 60 20. In a box car loader, the combination with a carriage and material distributing means thereon adapted to be inserted into and withdrawn from a car through one side thereof, of a chute adapted to be inserted into and withdrawn from the car through the op-
- posite side thereof and to deliver material to the said material distributing means within the car, a power driven shaft on the carriage and means for imparting movement in either direction to the said chute from said power driven shaft.
21. In a box car loader, the combination of a carriage, material distributing means thereon adapted to be inserted into and withdrawn from the car, a motor on the carriage, power transmitting mechanism interposed between said motor and said material distributing means, a chute for directing material to the said distributing means when within the car, and a train of power transmitting devices interposed between said motor and said chute for moving the latter relative to the carriage.
22. In a box car loader, the combination of a carriage, material distributing means thereon adapted to be inserted into and withdrawn from the car, a motor on the carriage, power transmitting mechanism interposed between said motor and said material distributing means, a chute for directing material to the said distributing means when within the car, and a train of power transmitting devices interposed between said motor and said chute, including a flexible cable and a winding drum and adapted to move the chute relative to the carriage.
23. In a box car loader, the combination of a distributing mechanism arranged to simultaneously deliver material to either end of a car, a carriage for moving said distributing mechanism into and withdrawing it from a car, a motor on said carriage, power transmitting mechanism including a clutch element interposed between said motor and the carriage driving wheels, and power transmitting mechanism including a clutch interposed between said motor and said material distributing mechanism.
24. In a box car loader, the combination of a material distributing mechanism, a carriage for said material distributing mechanism adapted to move it into and withdraw it from a car, a motor on said carriage having its armature shaft arranged longitudinally thereof, a main driving shaft in axial alignment with said armature shaft, power transmitting mechanism interposed between said driving shaft and said material distributing mechanism, and power transmitting means interposed between said drive shaft and the driving wheels for said carriage.
25. In a box car loader, the combination of a material distributing mechanism, a carriage for said material distributing mechanism adapted to move it into and withdraw it from a car, a motor on said carriage having its armature shaft arranged longitudinally thereof, a main driving shaft in axial alignment with said armature shaft, power transmitting mechanism interposed between said

6
driving shaft and said material distributing mechanism, and power transmitting means including a clutch interposed between said drive shaft and the driving wheels of the said carriage.

26. In a box car loader, the combination of a material distributing mechanism, a carriage for said material distributing mechanism adapted to move it into and withdraw it from a car, a motor on said carriage having its armature shaft arranged longitudinally thereof, a main driving shaft in axial alinement with said armature shaft, power transmitting means interposed between said drive shaft and said material distributing mechanism, and power transmitting means including a clutch interposed between said drive shaft and the driving wheels of the said carriage.

27. In a box car loader, the combination of a material distributing mechanism, a carriage for said material distributing mechanism adapted to move it into and withdraw it from a car, a motor on said carriage having its armature shaft arranged longitudinally thereof, a main driving shaft in axial alinement with said armature shaft, means for connecting one end of the said driving shaft with said armature shaft, and means for connecting its other end with said material distributing mechanism.

28. In a box car loader, the combination of a material distributing mechanism, a carriage for said material distributing mechanism adapted to move it into and withdraw it from a car, a motor on said carriage having its armature shaft arranged longitudinally thereof, a main driving shaft in axial alinement with said armature shaft, means for connecting one end of the said driving shaft with said armature shaft, means for connecting its other end with said material distributing mechanism, and a train of power transmitting devices interposed between said driving shaft and the driving wheels of the carriage.

29. In a box car loader, the combination with a movable carriage of a motor mounted on said carriage, power transmitting mechanism interposed between said motor and the

carriage driving wheels, a hopper supported upon said carriage and adapted to be inserted into and withdrawn from a car through one side thereof, material distributing means arranged within said hopper, and power transmitting mechanism interposed between 55 said motor and said distributing means.

30. In a box car loader, the combination of an endless conveyer arranged to be disposed longitudinally of a car to deliver material thereto, and having a drive shaft at its upper outer end, a carriage upon which said conveyer is supported and by means of which it is inserted into and withdrawn from the car, a motor on said carriage, a main drive shaft connected to said motor, and an 60 65 endless chain driving connection between said main drive shaft and the conveyer driving shaft.

31. In a box car loader, the combination of a longitudinally movable carriage, a material receiving hopper supported upon said carriage and arranged to be inserted into and withdrawn from a car, material distributing means mounted within said hopper and arranged to deliver material simultaneously at opposite ends of the car, a main drive shaft on the carriage, and power transmitting mechanism interposed between said main drive shaft and said material distributing means.

32. In a box car loader, the combination of a longitudinally movable carriage, a material receiving hopper rotatably mounted on said carriage and arranged to be inserted into and withdrawn from a car, material distributing means mounted within said hopper and arranged to deliver material simultaneously at opposite ends of the car, a main drive shaft on the carriage, and power transmitting mechanism interposed between said main drive shaft and said material distributing means.

In testimony whereof I have affixed my signature, in presence of two witnesses.

FREDERICK D. BUFFUM.
